UNITED STATES PATENT OFFICE

EDGAR E. GREVE, OF BELLEVUE, PENNSYLVANIA, ASSIGNOR, BY MESNE ASSIGNMENTS, TO OIL WELL SUPPLY COMPANY, OF PITTSBURGH, PENNSYLVANIA, A CORPORATION OF NEW JERSEY

TRAVELING BLOCK

Application filed September 10, 1925. Serial No. 55,506.

This invention relates to traveling blocks and more particularly to traveling blocks especially designed for use in connection with the drilling and operation of oil and other 5 wells.

Blocks of this character are usually of considerable size and weight and embody one or more sheaves for pulley ropes or cables, a supporting frame in which the sheaves are 10 mounted, and means for suspending the load therefrom. These blocks are employed for handling the tubing, casing, etc., and for raising and lowering the said tubing, casing, etc., in connection with the above stated work.

15 Among the objects of the present invention are, to provide a simple and efficient block of the character specified embodying means for resiliently supporting the sectional tubing or casing especially during the operation 20 of connecting and disconnecting the sections; a construction embodying guard means for the sheaves and the ropes while passing over the sheaves to prevent accidental contact therewith; means for providing efficient lubrication for the sheaves; a construction including 25 a plurality of sheaves having a common shaft and means whereby the common shaft may be readily removed from the block structure and a new one or a different type 30 of shaft inserted without disassembling the block; and a construction embodying means enabling the clevis carrier and clevis structure to be swung free of the block body in order to permit the body to rest upon its base 35 during the operation of stringing the line, i. e., passing the ropes or cables over the sheaves.

In the accompanying drawing, which illustrates an application of my invention—

40 Figure 1 is a side elevational view of a traveling block constructed in accordance with my invention and Figure 2, is a part sectional view and a part elevational view of the block, the elevation being at right angles to the view 45 of Figure 1.

As illustrated and as preferred the traveling block comprises two similar side members 2—2; these members constitute the body or frame of the block in which a 50 plurality of sheaves 3 are mounted. Each

side member is formed with an opening 4 through which a shaft 5 for the sheaves 3 extends; and each side member is further provided with openings 6 and 7 designed to receive tie-bolts or members 8 and 9 respectively. Shaft 5 has a nut 10 on each end and the respective ends of tie-bolts 8 and 9 are provided with nuts 11 and 12. It will be seen that the two side members are connected by the shaft 5 and its nuts and by the tie-bolts or members 8 and 9 and the nuts mounted thereon.

The openings 4 through which the ends of the shaft 5 project, are sufficiently large to permit of the shaft being passed therethrough and for the purpose of maintaining the shaft in position in the frame, I provide filler rings 13 and washers 14 at each end of the shaft. The filler rings are of the same diameter as the roller bearing cages 15, but the diameters 70 of the washers 14 are greater than the filler rings. The washers 14 are disposed between the filler rings and the nuts 10 and bear against the side frame members 2.

By means of this construction I am enabled to insert and remove the shaft 5 without removing the side members 2 or other parts of the block structure; further, with this construction a sheave and its bearing may be removed and inserted without disturbing 80 the said side members.

The construction illustrated is particularly adapted for lubrication. As illustrated, I provide horizontally extending passages 16 and radially extending passages 17 leading to the bearings 15 for the respective sheaves 3. It should be understood that in the block illustrated there are four sheaves and that passages similar to 16 and 17 are provided for the two sheaves not clearly shown. Lubricant is forced into the passages 16 through cap controlled openings 18 located at the ends of the shaft 5.

The frame comprising the two side members 2—2 has a flat base portion formed by the flat bottom faces 19 on each of the said side members. This base enables the frame or block body to be supported in an upright position after the clevis carrier and clevis structure are swung free of the said lower 100

ends of the side members, as will be more fully hereinafter described.

20 designates a series of spaced apart plates mounted on shaft 5 and tie-bolts 8 and 9; these plates when assembled as shown, form compartments for the respective sheaves and their bearings.

Pivottally connected to the upper tie-bolt 8 is a block supporting member 21, designed to be connected with a rope or cable, not shown. Member 21 is formed with end-members 22 encircling the tie-bolt and these ends together with members 23 constitute spacing means on the tie-bolt 8 for the plates 20.

15 For the purpose of covering the spaces between the upper portions of the side plates 2—2 adjacent the sheaves, in order to prevent accidental access to the sheaves and the ropes or cables thereon I provide two three-sided guard members 24. These members are secured to the side frame members by any suitable means, such as bolts 25 passed through lugs 26; these guards are provided with slot openings 27 through which the ropes 25 or cables are designed to pass. As shown, each guard member comprises side portions *a* having straight edges *b* for engagement with a side member and a continuous curved and slotted portion *c*.

30 Suspended within the frame, near its base portion and on the tie-bolt 9, is a clevis carrier structure 30. The carrier is provided with spring receiving pockets 31 extending vertically thereof. Each pocket has a lower 35 interior shoulder 32 and an upper shoulder 33.

33. The carrier is adapted to be swung on the bolt 9 in such a manner that it will be free of the base portion of the block frame, thereby permitting the block to stand upright 40 on its base portion when it is desired to string the line, or for other purposes. The clevis carrier is designed to carry a clevis device including in the structure illustrated, two vertically extending bolts 34 having their lower 45 ends passed through a cross member 35. The bolts extend downwardly through the said pockets 31 of the carrier and through the ends of the cross-member, the lower ends of the bolts being threaded to receive nuts 36 and 37. Disposed within each pocket and 50 surrounding the bolt 34 therein is a compression spring 38. Spring 38 is maintained in position between the shoulder 32 and a cap 39 carried on the upper ends of the bolts; the function of the springs is to resiliently 55 support the clevis and in turn the tubing, etc. that in operation, is suspended therefrom. The downward movement of the clevis relatively to its carrier is arrested by reason of 60 the cap 39 coming into engagement with the shoulder 33.

What I claim is:

1. A traveling block including a sheave frame having a supporting base portion 65 formed with a lower flat bearing face, a

clevis carrier, a pin disposed horizontally on said frame on which said carrier is pivoted, said pin being at an elevation to enable the carrier to be swung above the plane of said face so that the frame may stand on said face, a clevis, rods rising from the clevis and slidably mounted on the carrier and located below said face, cushioning springs engaged by the rods, said carrier, clevis and parts carried by the latter being in unitary relation.

70 2. A traveling block having a sheave frame, said frame having a supporting base portion, a clevis carrier, a pin on said frame on which the carrier is pivoted, said pin being at an elevation to enable the carrier to be swung above the plane of said base portion so that the frame may stand on the latter, and resiliently mounted clevis means on the carrier located below the said base portion in the supporting position of the clevis, said carrier and clevis means constituting a unit.

75 3. In a traveling block, a frame including spaced-apart side members, a plurality of sheaves mounted in the frame, and a pair of three-sided guards for the sheaves, each guard being secured to a side member and formed with flat side portions having straight edges for engagement with a side member of the frame, and an outer continuous, curved and slotted portion, lateral lugs on the side members embraced by the three sides of the guards, and bolts for securing the respective guards to the lugs, said slots continuing through the upper edge of the respective guards.

80 4. A traveling block having a sheave frame provided with a base on which it is adapted to rest, a clevis carrier, means pivoting said carrier to the frame at such an elevation to enable the carrier to be swung above said base to permit the frame to rest thereon, the pivotal mounting of the clevis carrier enabling the latter to rest on the same support as the frame, whereby the frame and carrier coact in the positioning of the frame 85 when it rests on its base.

100 5. A traveling block including a sheave frame capable of self-support in upright position, a clevis carrier pivoted on said frame and normally depending therefrom, a clevis, rods rising from the clevis and slidably mounted on the carrier, springs coacting with the rods, said carrier, clevis and parts associated therewith being in unitary relation whereby the movement of the carrier on its pivot will dispose them above the base of said frame, the pivotal mounting of the carrier enabling such unitary parts to engage the same support as the frame to aid in maintaining the latter in the aforesaid upright position.

105 In testimony whereof I affix my signature.
EDGAR E. GREVE.
